SEWING MACHINE

Clarence C. Smith, Chicago, Ill., assignor to Union
Special Machine Company, Chicago, Ill., a cor-
poration of Illinois

Application June 24, 1944, Serial No. 541,902

7 Claims. (Cl. 112—256)

1

This invention relates to sewing machines and, more particularly, to new and improved devices or apparatus associated or combined therewith for insuring proper and adequate lubrication of all moving parts of the sewing machine mechanism.

This invention is especially directed to certain new and improved instrumentalities or devices for insuring thorough lubrication of all parts of the machine requiring lubrication without, however, involving unnecessary pumping of the lubricating oil, or subjecting it to excessive working. It has previously been suggested to provide either full or semi-automatic lubrication of the parts of a sewing machine by means of a pump arranged to be driven by some operating part of the machine and adapted, throughout entire operation of the sewing machine mechanism, to draw oil from a low point and discharge it at the points within the machine which are to be lubricated. However, arrangements of this sort, wherein lubricating oil is continuously supplied to the parts to be lubricated while the machine is in operation, have subjected the oil to excessive working, since the oil is moved from one point to the other more rapidly than is required for adequate lubrication. In arrangements of this sort a large amount of the oil lifted from the lower reservoir to an upper level, whence it is supplied to the moving parts to be lubricated, must be returned to the lower reservoir by some means, usually by overflow, or it must be discharged over the parts of the machine to be lubricated at a more rapid rate than necessary. Under these conditions the oil deteriorates more rapidly than in lubricating systems wherein unnecessary and excessive working of the oil is avoided.

One of the objects of this invention is the provision in association with a sewing machine, of new and improved lubricating apparatus, devices, or instrumentalities, which provide adequate lubrication of the moving parts, the oil being pumped, however, only periodically, and not continuously during operation of the sewing machine. It has been found that this object may be most effectively achieved by providing pumping action for the purpose of elevating the oil from certain sumps or low points within the machine to a plurality of points from which it may be distributed to the moving parts to be lubricated only coincident with initiation of the operation of the sewing machine. Preferably this pumping action, elevating the oil from low points to distributing reservoirs at a higher level,

2

is carried out incidental to each stitching operation. In the ordinary use of a sewing machine the mechanism is started and stopped with sufficient frequency to insure adequate delivery of the lubricant to points within the apparatus for distribution to the moving parts so that thorough lubrication of all these parts is secured, even though the pump functions only momentarily, upon each operation of the machine.

10 It is another object of this invention to provide two separate oil circulating systems, including separate lubricant sumps and reservoirs, these separate systems being adapted to lubricate different sections of the sewing machine but being both made effective by operation of the same pumping means. By thus providing two separate lubrication systems the operation of each system is insured even though, through clogging or breakage, the operation of the other system may be interfered with. Moreover, the oil conduits are much shortened in length, thereby allowing more rapid and efficient oil circulation, at the same time avoiding excessive working. Two separate systems also allow the use 15 of lubricants of different grade in the separate systems, which may sometimes be desirable.

It is still another object of this invention to arrange the lubricating systems in such a manner as to permit ready accessibility to thread 20 take-up devices enclosed within the frame of the machine.

25 A further object of this invention is to provide means whereby, if desired, the lubricant reservoirs may be by-passed and lubricant supplied directly to a point requiring abundant and complete lubrication, such as the bearings of the needle lever.

The foregoing objects, features, and advantages of this invention, as well as others which 30 will be hereinafter set forth, are evident from the ensuing disclosure of certain illustrative embodiments thereof. The preferred arrangements of these illustrative embodiments may be readily understood from the detailed description 35 which will now be given in connection with the annexed drawings wherein:

Fig. 1 is a rear elevation of the sewing machine, certain parts being broken away for clearness of illustration;

50 Fig. 2 is a front elevation of a sewing machine to which the invention has been applied, portions thereof being broken away for clearness of illustration;

55 Fig. 3 is a top plan view of the sewing machine, certain cover plates and other parts being re-

moved or broken away and some parts being shown in section, in order to illustrate the construction more clearly;

Fig. 4 is a view in plan of the oil inlet apertures in the top of the frame whereby oil is supplied to one of the separate, independent oil reservoirs in the frame, these inlet apertures being normally covered with a transparent dome-like member provided for observing the oil as it is pumped;

Fig. 5 is a vertical cross-sectional view taken through one of the transparent domes provided for observance of the oil, this dome being positioned to cover the oil openings shown in Fig. 4;

Fig. 6 is a fragmentary view, partly in elevation and partly in vertical section, showing the needle head portion of the machine and the arrangement of certain parts associated therewith.

Fig. 7 is a longitudinal sectional view through the improved double-acting four valve pump forming part of the lubrication system;

Fig. 8 is a plan view of an alternative form of transparent dome structure provided for observing the oil which is fed into the independent reservoirs provided in the upper portion of the frame through the openings shown in Fig. 4;

Fig. 9 is an elevational view of the transparent dome shown in Fig. 8, this view showing the securing means by which the transparent dome is secured to the top of the sewing machine frame, the latter being shown in section.

Fig. 10 is a horizontal cross-sectional view through the alternative form of dome shown in Figs. 8 and 9, this view being taken on the line 10—10 of Fig. 9;

Fig. 11 is a vertical cross-sectional view through the alternative form of transparent dome, this view being taken on the line 11—11 of Fig. 10;

Fig. 12 is a partial top plan view of the sewing machine, certain cover plates and other parts being removed or being broken away, and some parts being shown in section, in order to illustrate the invention more clearly. This view shows a modified construction in which lubricant is supplied directly from the pump to the bearings for the needle lever, these bearings not being supplied from a reservoir as in the construction shown in Fig. 3;

Fig. 13 is a detail view, in vertical section, showing a portion of the end of the work supporting arm; and

Fig. 14 is a perspective view of a complete assembly embodying the invention, including a supporting table with a sewing machine thereon, a driving motor and clutch unit beneath the tabletop, and suitable control devices.

For purposes of illustration the invention has been shown as applied to a feed-off-the-arm machine of the type disclosed in Christensen and Le Vesconte Patent 1,741,095. Reference may be had to that patent for a fuller disclosure of certain features of construction and operation not essential to an understanding of this invention which are set forth in detail therein. Certain other features of operation and construction, not given in detail herein, may be found described in Christensen patent application Ser. No. 465,947, filed November 18, 1942, now matured into Patent No. 2,372,175, dated March 27, 1945.

Referring to the drawings, the sewing machine includes supporting structure such as a table top 10 (Fig. 14) on which is mounted a sewing machine designated generally at 11. The sewing machine includes frame 12 which may be constructed as shown in the Christensen et al. patent. It includes downwardly extending hollow

portion 12a and work supporting arm 12b. Power is supplied to the machine through a combined hand wheel and pulley 13, secured to a main drive shaft 14 extending longitudinally of the upper portion of the frame (Figs. 2, 3, and 12). The power delivered may be supplied by an electric transmitter including motor 15 and associated clutch 16 which may be of any known construction such as that shown, for example, in the co-pending application of Le Vesconte and Schweda, Ser. No. 449,196, filed June 30, 1942, now matured into Patent No. 2,390,220. The driven member of the clutch is connected with pulley 13 by means of belt 17. When the machine is in use the motor 15 will be in constant operation, but the sewing machine will be driven only upon engagement of the clutch, which is effected under control of arm 18 adapted to be drawn downwardly by link 19 connected with rock arm 29 carried by rock shaft 21. Foot treadle 24 is connected with another arm 22, secured to rock shaft 21, by means of link or rod 23. When the foot treadle is rocked by the operator the sewing machine may be operated whenever desired. The rocking of the foot treadle not only serves to bring about operation of the sewing machine but, as will be subsequently explained, also controls the pumping of oil from the main oil sumps to reservoirs at an upper level for distribution to the moving parts. In fact the connections are such that the pump may be operated to some extent by a limited movement of the treadle which is not sufficient to cause engagement of the transmitter clutch. Thus, oil may be pumped from the lower sumps to the higher reservoirs without operating the sewing machine even while the motor is running.

The shaft 14 is advantageously formed in several sections, these sections being journaled in appropriate bearing sleeves 25, 26, 27 and 28, all carried by the frame. The two main sections of the shaft are connected by a coupling 14a. Collars 29 and 30, secured to the main sections of the shaft at opposite sides of the coupling, serve to take up the thrust in both directions cooperating, for this function, with suitable surfaces on the frame. An excess lubricant collecting chamber 31 is provided at the top of the frame around coupling 14a and collars 29 and 30.

Between bearings 25 and 28 (Fig. 3) within chamber 32 formed in the top of the frame, the shaft 14 is provided with a crank portion 33 (Fig. 6) extending between counterweights 33a (Fig. 3) formed integral with, or secured in some other manner, to adjacent portions of the shaft. Pitman 34 cooperating with the crank 33 is pivotally connected at its opposite end by pin 35 (Fig. 6) with the downwardly extending arm of bell crank lever 36 rockably mounted upon the frame by means of shaft 37. This shaft is journaled in bushings 38 and 39 (Fig. 3) carried by the needle head portion of the frame.

The outer end of the forwardly extending arm of bell crank 36 is connected by link 40 through pivot 41 with block 42 secured to needle bar 43. This needle bar is mounted for vertical reciprocation in the needle head in the manner well known in the sewing machine art. Also mounted for vertical reciprocation in the needle head is presser bar 45 carrying at its lower end presser foot 46 (Fig. 2) which may be of any suitable form. The presser bar 45 is urged downwardly by means of a spring arrangement 47 of any suitable form. For the purpose of lifting the presser foot against the action of the spring there is provided block 48 (Fig. 6) secured to the presser

bar, which block is adapted to be engaged by finger 49 secured to rock shaft 50. An arm 51 is also secured to the rock shaft and is connected by link 52 with an upward extension of lever 53 secured to rock shaft 54, which rock shaft is mounted on a portion of the frame. The other end of the lever 53 is connected by a chain 55 with a foot treadle or any other convenient control member (not shown), operable at will by the machine operator.

Adjacent the presser bar and presser foot there is provided thread controller mechanism including C-shaped link 551 attached to the lower end of a vertical sliding rod 552 mounted in suitable bearings 553 carried by the end cover plate 554 of the needle head. The lower end of link 551 is connected with the forward section of the presser foot 46 which is tandem construction. At its upper end the rod 552 carries forked member 555, the forked free end of which is adapted to straddle and slide along the presser bar 45, thus preventing rotation of the rod 552. Intermediate the ends of the rod 552 there is secured block 556 having a laterally projecting portion which is in operative connection with certain thread guiding and controlling means (not shown). This mechanism, including C-shaped link 551, operates as a thread controller for varying the amount of needle thread available for the stitch-forming operation. The detailed operation of this mechanism, as well as that of the pressure foot, need not be described in further detail for a full understanding of the present invention relative to sewing machine lubrication. For description in detail of the thread controller and its mode of operation, see the copending application of Christensen Ser. No. 513,336, filed December 8, 1943.

Adjacent the inner end of shaft 14 there is secured an eccentric 56 which cooperates with the strap portion of pitman 56a (Fig. 2). At its lower end (not shown), this pitman is connected in a suitable manner with a feed bar 57 and feed dog 58 (Fig. 13), this mechanism serving to impart a rising and falling movement to the feed dog, which is preferably of the four-motion type. The operation of such a feed dog, and the mechanism for imparting rising and falling movements thereto, are described in the Kucera Patent 2,199,666, issued May 7, 1940.

Shaft 14 carries a second eccentric 59 which cooperates with strap portion of pitman or link 59a which, through suitable connections of the type disclosed in said Kucera patent, serves to impart the feed stroke and return movements to the feed dog. This mechanism also serves to impart the desired needle avoid movements to the loopers, hereinafter mentioned. The end of shaft 14 carries crank pin 60 cooperating with a pitman or linkage 61, the lower end of which is connected with an arm 62 secured to the rock shaft 63. This shaft carries one or more loopers 64 which operate in stitch formation with needles 44.

The improved lubricating system, to which this invention is particularly directed, includes double-acting four valve reciprocating pump 65, suitably mounted, as by means of screws, upon a portion of the frame 12 of the machine. The pump 65 has a plurality of inlets, one of which is connected by a pipe or tube 66 with the main sump 67 (Fig. 1) provided in downwardly extending hollow portion 12a of frame 12. The other inlet of the pump 65 is connected by a pipe or tube 68 with a similar sump 69 provided at the rear of the needle head portion of frame 12 (Fig. 6). The

lower ends of the tubes 66 and 68 are preferably provided with suitable strainers or filters 70 and 71, respectively, to insure the circulation of only clean oil.

One outlet of the pump is connected by tube 721 with dome 722, preferably formed of plastic or other transparent material, and by outlet 723 with a second transparent dome 724. Each of these domes may be constructed as shown in Fig. 10, 5, or in the alternative form shown in Figs. 8 to 11, inclusive, as more fully described below. Because of these transparent domes the operator of the machine may observe the character of the oil being pumped at any time, and may determine whether or not the system is functioning properly. Dome 722 is positioned directly above reservoir 725 suitably mounted upon the frame beneath a cover plate 760 (Fig. 2), which is also secured by screws or otherwise to the machine frame. Similarly, dome 724 is positioned above reservoir 726 mounted on the frame beneath a cover plate 761.

With particular reference to Fig. 7, the double-acting pump illustrated in this figure comprises 25 a cylinder or chamber 78 in which a piston 79 formed of opposed cup-shaped members is mounted for reciprocation. This piston is carried at the inner end of a rod 80 having its outer end connected by link 81 with the elbow of L-shaped lever 82 (Fig. 1). This lever is pivotally connected at 83 with the frame of the machine. The arm 84 of lever 82 projects beyond the pulley 13 and has its outer end connected by a chain 85 or other suitable means with the foot treadle 24. 35 This arrangement is such that when the treadle is depressed to cause engagement of the driving clutch, the rod 80 and the piston 79 will be shifted toward the left (Figs. 1 and 7) against the action of spring 86. The latter is compressed between 40 an enlarged head 861 on the end of the rod 80 and a combined bushing and stuffing box 87 which is threaded into and closes one end of the cylinder 78 and provides a substantially oil-tight sliding fit with the rod 80.

45 As the piston 79 is shifted toward the left (Fig. 7), oil will be drawn through tube 68 from sump 69 in the needle head, through ball valve 88, and delivered through duct 89 into the right-hand end of the cylinder 78. Simultaneously, oil 50 which has previously been drawn into the cylinder 78 at the left side of the piston 79, will be forced by the latter through duct 90, through ball valve 91, and through passage 92 into the discharge tube or conduct 721. When the treadle 24 is 55 rocked in the opposite direction, or is permitted to move in this direction by the action of the spring 86, the piston 79 is shifted toward the right (Fig. 7). Oil will then be drawn through tube 66 from sump 67 (Fig. 1) through ball valve 93, 60 and delivered through duct 90 into the left hand end of the cylinder 78. Simultaneously oil which has previously been drawn into the cylinder at the right side of the piston 79 will be forced by the latter through duct 89 past ball valve 94 and 65 through passage 941 into the discharge tube or conduit 723.

70 It is thus evident that oil is drawn alternately from the two sumps 67 and 69 upon the movement of the piston 79 in opposite directions. The pump will operate through only a single cycle upon each starting and stopping of the machine, i. e., upon each stitching operation. It is not operated continuously during the stitching operation, and therefore does not produce excessive working of the oil. Sufficient oil is pumped, however, to in-

sure adequate lubrication of all parts requiring lubrication. Moreover if one of the sumps should become dry, or nearly so, the pumping of oil from the other sump will not be interfered with. At the same time if the level of oil in one of the sumps drops to such a point that the withdrawal of oil therefrom ceases, or is seriously decreased, this fact may be quickly noted by the operator because little or no oil will be discharged into dome 722 or 724 at either the commencement or conclusion of the stitching operation, depending upon which of the two sumps happens to be empty or nearly empty.

The pump cylinder 78 is closed at one end by removable screw block 95, which facilitates cleaning and inspection of the working parts. The ball valves 91 and 94, associated with outlet or discharge conduits 721 and 723, are spring-pressed by springs 97 and 971. Ball valve 88 is carried by a fitting having a tapered nipple 98 in screw threaded engagement with a recess in the pump block. The inner end of the nipple is partially closed by hollow block 99 against which bears one end of spring 100 acting at its opposite end to urge the valve 88 against its seat.

In a similar manner valve 93 is mounted within the nipple extension of a fitting 101 which is partially closed by a hollow block 102 against which a spring 103 bears in urging the valve 93 against its seat.

Outlet ball valves 91 and 94, spring-urged against their seats by springs 97 and 971, are similarly mounted within tapered nipples 973 and 974 which are partially closed at their respective inner ends by hollow blocks 991 and 992. The springs 97 and 971 are so arranged as to force the balls 91 and 94 against the ends of hollow blocks 991 and 992, which ends provide the valve seats.

Each of the tubes 66, 68, 721 and 723 is preferably provided near its end with an enlargement in the form of a double frusto-conical compression sleeve 104 adapted to be clamped between an appropriate seat on a coupling member 105 and a corresponding seat formed on one of the inlets or the outlets of the pump.

The oil which is withdrawn from sumps 67 and 69 and pumped to discharge into the reservoirs 725 and 726, in the manner set forth, is delivered through tubes filled with wicking to certain portions of the sewing machine to be lubricated. Referring first to reservoir 726 (Figs. 2 and 3), it will be evident that part of the oil travels downwardly through oil hole 801 in a downwardly extending member 802 integral with the reservoir to bushing 25, this oil serving to lubricate the main shaft 14 journaled in that bushing. As shown, there is provided packing or wicking 115 which serves to retain part of the oil, delivering it as needed to the bushing 25.

The reservoir 726 is further provided with a laterally extending wick-filled oil pipe 805 which extends above the main shaft 14 and delivers oil to the bearing provided by bushing 26. There is provided packing or wicking 807, similar to packing or wicking 115, to retain the oil and feed it gradually, as needed, to the shaft 14 journaled in bushing 26.

A second wick-filled oil pipe 809 extends downwardly from the reservoir 726 adjacent the forward side of a wall member 810 of the frame and delivers oil to a recessed extension of the bushing 25. From the latter the oil is delivered to a small pocket formed by an inclined flange portion 811 of one of the counterweights 33a. Due

to the inclination of the inner surface of the flange portion 811, the oil is forced centrifugally into a duct 118 (Fig. 6) in the crank 33 from which it is distributed to lubricate the bearing surface of pitman 34. Pitman 34 is further provided with longitudinally extending oil duct 119 which supplies oil to the pivot bearing 35, between the pitman and needle lever 36.

The reservoir 726 is provided with a third oil pipe 821 which delivers oil to the bearings for the needle lever at 822 (Fig. 3), from which a laterally extending oil groove 823 distributes oil to the bearing bushings 38 and 39. A fourth oil tube 831 (Fig. 3) leading from the reservoir 726 terminates adjacent the path of link 40 which connects the end of the needle lever 36 to the needle bar 43 and keeps the pivot pins for this link well lubricated. A fifth oil tube 901 extends from the reservoir 726 above the crank 33 and delivers oil to the bearing bushing 28. The reservoir 726 is also provided with an overflow notch 910 (Fig. 3). All of the oil issuing from the various outlets of the reservoir 726, except a portion of the oil from the bearing journaled in bushing 26, will be collected in the needle head sump 69, and will be recirculated to the parts in the region of the needle head by pump 65 through conduit 723, while the oil collected in the work arm sump 67 will be recirculated to lubricate the parts in the region of the work arm through conduit 721.

Referring now to reservoir 725 (Fig. 2), the oil from dome 722 will pass through ports 210 and 211 into this reservoir which is supported from cross member 213 of the frame which serves also as a support for bushing 27. The reservoir 725 is provided with a downwardly extending portion 220 which fits into an opening 221 in the cross member. Oil in the reservoir 725 will pass down through aperture 222 in the portion 220 to bushing 27 and lubricate the shaft 14 in that bearing. As shown, hole 221 may be provided with packing or wicking in order to retain the oil, delivering it as needed to the portion of main shaft 14 journaled in bushing 27.

The reservoir 725 is further provided with downwardly extending oil pipes 301, 302, and 110, which are wick-filled, and which are located adjacent the upper ends of the pitmans 56a, 59a and 61, respectively, thus supplying oil for lubricating the bearing surfaces of the eccentric members 56 and 59 and crank pin 60. The reservoir 725 is further provided with a notch 303 at its upper edge which serves as an overflow. Waste lubricant from the reservoir 725 thus finds its way to the well or sump 67 in the bottom of the work arm.

The transparent dome members 722 and 724 may be constructed simply in the form of hollow cup-shaped members, as shown in Figs. 2 and 5, or they may be constructed in the form of solid transparent blocks of glass or plastic material provided with internal conduits, as shown in the modification of Figs. 8, 9, 10 and 11.

Referring to the modification shown in Fig. 5, the transparent dome structure includes hollow cup-shaped member 901 secured by a bolt or other securing means 902 to the cover member 760 at the top of the sewing machine frame, the dome being positioned directly over lubricant admission apertures 210 (Fig. 4). The cup-shaped member 901 is supported on ring 903, which may be of metal or some flexible material, such as rubber, capable of forming a seal. Conduits 721 and 723 from the pump supply lubricant to the interiors of the transparent dome mem-

bers, from which it flows through oil apertures 210 into reservoirs 725 and 726. Means are provided, as by directing the entering ends of conduits 721 or 723 laterally or even downwardly, to avoid splashing the oil against the interior surfaces of the cup-shaped member 901 so that the operator's view of the oil stream being supplied to reservoirs 725 and 726 is not interfered with.

In the modification shown in Figs. 8, 9, 10 and 11, the solid transparent dome member 910, of plastic, glass, or other transparent material, is provided with drilled, laterally extending conduit 911 in communication with another drilled conduit 912 at right angles thereto. Conduit 911 is in communication with lubricant pipe line 721 or 723 from the discharge side of the pump, while communicating conduit 912 leads to apertures 210, communicating directly with reservoir 725 or 726. As in the modification shown in Fig. 5, the solid transparent dome member 910, illustrated in Figs. 8 to 11, is positioned on the cover member 760 or 761 over the apertures 210 (Fig. 4), and rests on supporting and sealing ring 903.

It will be apparent that by the arrangement shown all the parts of a sewing machine requiring lubrication may be effectively lubricated with minimum working and circulation of the oil. Thus, the oil utilized for the lubrication of parts in and adjacent the needle head will be circulated through a relatively short path between the sump 69 in the needle head and the reservoir 726. Similarly, the oil serving to lubricate those parts of the machine in the depending arm 12a will be circulated merely between the sump 67 at the bottom of this arm and the reservoir 725. Two independent reservoirs, separate and distinct from each other, are thus provided, lubricant from these reservoirs being circulated by the wick-filled oil pipes, or otherwise, to the specific parts adjacent those reservoirs which require lubrication. Each reservoir is provided with separate conduits leading to the double-acting, four-valve pump 65 from which the lubricant is pumped, and with its separate transparent dome, whereby the supply of oil and the condition of the oil circulated may be observed by the operator.

In the modification of the invention shown in Fig. 12, lubrication is supplied directly from the pump 65 by conduit 723 to the bearings 38 and 39 for the needle lever. Conduit 723 is provided at its upper surface with a discharge hole 143 at a point over the reservoir 726 and when the pump operates to discharge oil through this pipe some of the oil will be projected out of this hole and against the under surface of transparent dome 724, from which it will drop into the reservoir 726. As will be seen, the dome 724 is positioned somewhat further to the left in this construction than in Fig. 3. From reservoir 726 the oil is distributed, as in the modification shown in Fig. 3 and described above, to the various parts of the machine to be lubricated. In this way the lubricant necessary to lubricate an important bearing in the machine, which needs an abundant supply of the lubricating oil, may be channelled directly to that part, by a conduit in direct communication with the pump, while other bearing surfaces may be supplied less directly from the reservoir.

While an illustrative form of the invention has been disclosed in considerable detail, it should be understood that numerous changes may be made in the construction and arrangement of the various parts without departing from the general principles and scope of the invention.

For example, while the lubricating system, the double-acting four-valve pump, and the other associated parts, are especially suited for use in connection with a feed-off-the-arm machine of the type illustrated, certain features are applicable to other types of machines, and to machines mounted from other types of supporting structures.

I claim:

- 10 1. In combination, a sewing machine and means associated therewith for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir in order that said moving parts may be lubricated, a plurality of separate lubricant collecting sumps in said machine each related to one of said reservoirs, and common lubricant pumping means operated by said means for controlling clutch engagement and disengagement, said pumping means being arranged to alternately withdraw lubricant from said sumps and to deliver said lubricant to the related reservoirs without intermixture of the lubricant in one reservoir and related sump with that in another reservoir and related sump.
- 15 2. In combination, a sewing machine, means connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent said reservoir which are to be lubricated, a plurality of separate lubricant collecting sumps in said machine each arranged to collect the lubricant delivered from one of said reservoirs, and common lubricant pumping means operable with said clutch engaging and disengaging means for withdrawing lubricant from one of said sumps upon engagement of the clutch and delivering said lubricant to the related one of said reservoirs, and for withdrawing lubricant from another of said sumps upon disengagement of the clutch and delivering said lubricant to its related reservoir.
- 20 3. In combination with a sewing machine, means connected with said machine for driving the same, means operable at will for controlling the engagement or disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 25 4. In combination, a sewing machine, driving means including a clutch connected with said machine for driving the same, means operable at will for controlling the engagement and dis-
- 30 5. In combination, a sewing machine, means connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent said reservoir which are to be lubricated, a plurality of separate lubricant collecting sumps in said machine each arranged to collect the lubricant delivered from one of said reservoirs, and common lubricant pumping means operable with said clutch engaging and disengaging means for withdrawing lubricant from one of said sumps upon engagement of the clutch and delivering said lubricant to the related one of said reservoirs, and for withdrawing lubricant from another of said sumps upon disengagement of the clutch and delivering said lubricant to its related reservoir.
- 35 6. In combination, a sewing machine, means connected with said machine for driving the same, means operable at will for controlling the engagement or disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 40 7. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 45 8. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 50 9. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 55 10. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 60 11. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 65 12. In combination, a sewing machine, driving means including a clutch connected with said machine for driving the same, means operable at will for controlling the engagement and disengagement of the clutch to effect successive operations of the machine, a plurality of separate lubricant reservoirs in said machine, means connected with each of said separate reservoirs for delivering lubricant to the moving parts adjacent each reservoir to be lubricated, a plurality of separate lubricant collecting sumps in said machine each related to and arranged to collect the lubricant delivered from one of said reservoirs, and means including
- 70 13. In combination, a sewing machine, driving means including a clutch connected with said machine for driving the same, means operable at will for controlling the engagement and dis-

11

engagement of the clutch to effect successive operations of the machine, a plurality of separate reservoirs for lubricant within said machine arranged to deliver oil to parts to be lubricated, and lubricant circulating and distributing means comprising a plurality of separate oil collecting sumps in said machine each related to and arranged to receive lubricant from one of said reservoirs, a reciprocating piston pump arranged to withdraw oil from only one of said sumps upon movement of the piston in one direction, and from only another of said sumps upon movement of the piston in the opposite direction, and means for delivering the oil so withdrawn from each sump to its related lubricant reservoir within said machine.

5. In combination, a sewing machine having stitch-forming instrumentalities adapted to form a seam, means operable at will as an incident to each seam-forming operation, and lubricant circulating and distributing means comprising a plurality of separate oil reservoirs arranged to deliver oil to parts to be lubricated, a plurality of separate oil collecting sumps in said machine each related to and arranged to receive lubricant from one of said reservoirs, pump means arranged to withdraw oil from one of said sumps upon operation of said first named means and to withdraw oil from another of said sumps upon release of said means, means for supplying the oil so withdrawn from each of said sumps to its related oil reservoir, and means for delivering said oil from said reservoir to the parts of the machine to be lubricated.

6. In combination, a sewing machine having stitch-forming instrumentalities adapted to form a seam, means operable at will as an incident to each seam-forming operation, and lubricant circulating and distributing means comprising a plurality of separate oil reservoirs in said machine arranged to deliver oil to parts to be lubricated, a plurality of separate oil collecting sumps each related to and arranged to receive lubricant from one of said reservoirs, a reciprocating pis-

12

ton pump, connections from said first mentioned means for reciprocating the piston of said pump, said pump being arranged to withdraw oil from one of said sumps upon movement of said piston in one direction, and to withdraw oil from another of said sumps upon movement of the piston in the opposite direction, means for supplying said oil so withdrawn from each of said sumps to its related oil reservoir, and means for delivering the oil from said plurality of reservoirs to the moving parts to be lubricated.

7. In combination, a sewing machine having a frame with a needle head portion and a hollow downwardly-extending portion from which a work supporting arm extends to a point beneath the needle head portion, said needle head portion and said arm having stitch forming instrumentalities adapted to form a seam, means operable at will as an incident to each seam-forming operation, and lubricant circulating and distributing means comprising a plurality of oil collecting sumps in said needle head portion and work supporting arm, respectively, a plurality of separate oil reservoirs within said machine each related to one of said sumps, pump means controlled by said first named means and arranged to withdraw oil alternately from said sumps, means for delivering said oil so withdrawn from each sump to the related one of said separate reservoirs, and means for supplying the oil from said separate reservoirs to the moving parts to be lubricated.
